(57) **CLAIM**

The ornamental design for an adherable diffuser, as shown and described.

DESCRIPTION

FIG. 1 is a rear perspective view of an adherable diffuser with top door in open position in a configuration of use; FIG. 2 is a front perspective view of an adherable diffuser thereof;

FIG. 3 is a top view of an adherable diffuser thereof; FIG. 4 is a bottom view of an adherable diffuser thereof; FIG. 5 is a left side view of an adherable diffuser thereof; FIG. 6 is a right side view of an adherable diffuser thereof; FIG. 7 is a front view of an adherable diffuser thereof; FIG. 8 is a rear view of an adherable diffuser thereof; FIG. 9 is a rear perspective view of the adherable diffuser of FIG. 1 with top door in closed position in an alternate configuration of use;

FIG. 10 is a front perspective view of an adherable diffuser thereof;

FIG. 11 is a top view of an adherable diffuser thereof; FIG. 12 is a bottom view of an adherable diffuser thereof; FIG. 13 is a left side view of an adherable diffuser thereof; FIG. 14 is a right side view of an adherable diffuser thereof; FIG. 15 is a front view of an adherable diffuser thereof; and FIG. 16 is a rear view of an adherable diffuser thereof.

FIG. 17 is a front perspective view of the adherable diffuser of FIGS. 1 and 9 showing cartridge drawer in open position in an alternate configuration of use;

FIG. 18 is a top view of an adherable diffuser thereof; FIG. 19 is a bottom view of an adherable diffuser thereof; FIG. 20 is a left side view of an adherable diffuser thereof; FIG. 21 is a right side view of an adherable diffuser thereof; FIG. 22 is a front view of an adherable diffuser thereof; and, FIG. 23 is a rear view of an adherable diffuser thereof.
